5 Claims. (Cl. 260—397.45)

This invention relates to an improved process for the hydrolysis of certain steroid 3-enamines to the corresponding 3-keto steroids, more particularly to an improvement in the alkaline hydrolysis of the 3-pyrrolidyl enamine of 6α -methyl- $11\beta,21$ -dihydroxy-4,17(20)-pregnadien-3-one which comprises converting the 3-enamine to an acid addition salt thereof prior to the alkaline hydrolysis.

The alkaline hydrolysis of 3-enamines is a known reaction [Hogg et al., J. Am. Chem. Soc., 77: 4436 (1955)]. However, when this reaction was applied to the 3-pyrrolidyl enamine of 6α -methyl- $11\beta,21$ -dihydroxy-4,17(20)-pregnadien-3-one [Spero et al., J. Am. Chem. Soc., 78: 6213 (1956)], the yield of desired 6α -methyl- $11\beta,21$ -dihydroxy-4,17(20)-pregnadien-3-one was considerably less than was obtained when the corresponding hydrolysis was conducted on the 3-pyrrolidyl enamine of $11\beta,21$ -dihydroxy-4,17(20)-pregnadien-3-one. Whereas the hydrolysis of the latter compound at room temperature produced satisfactory yields, the hydrolysis of the former compound under the same conditions gave only a 20% yield of desired product, calculated on the starting 3,11-diketo- 6α -methyl-4,17(20)-[cis]-pregnadien-21-oic acid methyl ester. Even prolonged heating raised the yield only slightly.

We have now found that when the 3-pyrrolidyl enamine of 6α -methyl- $11\beta,21$ -dihydroxy-4,17(20)-[cis]-pregnadien-3-one, i.e., 3-pyrrolidyl-6-methyl- $11\beta,21$ -dihydroxy-3,5,17(20)-[cis]-pregnatriene, is converted to an acid addition salt thereof prior to the hydrolysis, an over-all yield of about 40-50%, calculated from the starting 3,11-diketo- 6α -methyl-4,17(20)-[cis]-pregnadien-21-oic acid methyl ester, can be achieved even without heating. Whereas the hydrolysis reaction without the acid addition salt step required chromatographic separation in order to isolate the desired product, the process of this invention gave more than twice the amount of product by direct crystallization, an advantage of particular significance in commercial production. This increase in yield of an intermediate useful in the production of the highly active anti-inflammatory agent 6α -methyl- $11\beta,17\alpha,21$ -trihydroxy-4-pregnene-3,20-dione 21-acetate, is particularly significant in view of the number of steps necessary for its production (Spero et al., *supra*).

The starting compound in the process of this invention is the 3-pyrrolidyl enamine of 6α -methyl- $11\beta,21$ -dihydroxy-4,17(20)-pregnadien-3-one, especially the 3-pyrrolidyl enamine of 6α -methyl- $11\beta,21$ -dihydroxy-4,17(20)-[cis]-pregnadien-3-one, which is prepared from 3,11-diketo-4,17(20)-pregnadien-21-oic acid methyl ester (Spero et al., *supra*).

These enamines are converted to an acid addition salt by reaction with an inorganic or organic acid in the usual manner for the production of amine acid addition salts. However, if aqueous conditions are employed, it is preferred that the solution or suspension containing the acid

addition salt is made alkaline immediately as the yield of desired product is reduced when the 3-enamine is maintained under aqueous acidic conditions for prolonged periods. Moreover, because of the presence of the labile 11β -hydroxy group, heating under aqueous acidic conditions should be avoided.

Acid addition salts which may be employed include both inorganic and organic acid addition salts, preferably the latter, especially lower-hydrocarbon carboxylic acid addition salts, i.e., containing from 1 to 8 carbon atoms. Representative acid addition salts, e.g., prepared from the corresponding 3-enamine and acid, include the hydrochloride, hydrobromide, sulfate, phosphate, nitrate, acetate, formate, propionate, butyrate, chloroacetate benzoate, trichlorobenzoate, trifluoroacetate, etc.

The following preparation and example are illustrative of the process of this invention, but are not to be construed as limiting.

PREPARATION

20 3-pyrrolidyl- 6α -methyl- $11\beta,21$ -dihydroxy-3,5,17(20)-[cis]-pregnatriene:

A solution of 3.7 g. of 6α -methyl-3,11-diketo-4,17(20)-[cis]-pregnadien-21-oic acid methyl ester [Spero et al., 25 J. Am. Chem. Soc., 78: 6213 (1956)], 70 mg. of p-toluenesulfonic acid and 1.65 ml. of pyrrolidine in 75 ml. of benzene was refluxed for one hour with the water formed during the reaction being continuously separated from the refluxing benzene in a Dean-Stark trap. The solvent was then removed under vacuum. The residue, consisting essentially of 3-pyrrolidyl- 6α -methyl-11-keto-3,5,17(20)-[cis]-pregnatrien-21-oic acid methyl ester, was dissolved in 50 ml. of anhydrous ether and then added to a suspension of 1.2 g. of lithium aluminum hydride 30 in 100 ml. of ether. After heating under reflux for one hour, the reaction mixture was cooled and then 7.5 ml. of ethyl acetate was cautiously added followed by 18 ml. of water to precipitate the inorganic salts as a thick paste. The ether phase contained the dissolved 3-pyrrolidyl- 6α -methyl- $11\beta,21$ -dihydroxy-3,5,17(20)-[cis]-pregnatriene.

The corresponding trans isomer is prepared by starting with methyl 3,11-diketo-4,17(20)-[trans]-pregnadien-21-oic acid methyl ester which, in turn, is prepared by refluxing a methanolic solution of the corresponding cis isomer in the presence of sodium methoxide.

EXAMPLE

50 6 α -methyl- $11\beta,21$ -dihydroxy-4,17(20)-[cis]-pregnadien-3-one

A. OLD METHOD

The total reaction mixture obtained as described in the preparation and containing the 3-pyrrolidyl- 6α -methyl- $11\beta,21$ -dihydroxy-3,5,17(20)-[cis]-pregnatriene was distilled to dryness under vacuum and the residue covered with nitrogen and to it was then added 125 ml. of methanol. After stirring at 25° C. for 5 minutes, 10 ml. of 5% sodium hydroxide was added. The reaction mixture was stirred at 25° C. for 1.5 hours. The pH of the mixture was adjusted to 7 with 3 ml. of acetic acid and the solvent distilled under vacuum. A solution of 12.5 ml. of concentrated hydrochloric acid in 200 ml. of water was added. The product was extracted from the resulting mixture with methylene chloride. The solution was dried and the methylene chloride distilled. The 3 g. residue was dissolved in ethyl acetate and seeded, but crystals failed to form so the solution was evaporated to dryness, redissolved in 400 ml. of methylene chloride and chromatographed over 240 g. of magnesium silicate (Florisil). The column was developed with hexanes (Skellysolve B) containing increasing proportions of ace-

3

tone. 1.03 g. of $11\beta,21$ -dihydroxy-4,17(20)-[*cis*]-pregnadien-3-one was eluted with hexanes plus 20% acetone and hexanes plus 30% acetone. No significant amount of this compound was present in any of the other eluate fractions. Purification of this compound by crystallization from ethyl acetate gave 0.7 g., a yield of 20% of the theoretical, calculated from the starting 3,11-diketo- 6α -methyl-4,17(20)-[*cis*]-pregnadien-21-oic acid methyl ester, of crystals melting at 172-174° C., having an $[\alpha]_D$ of +125° (CHCl_3) and a

$\lambda_{\text{max.}}^{\text{Hc}}$ of 242, a_M 15,200

B. NEW METHOD

The ether layer obtained as described in the preparation and containing the 3-pyrrolidyl-6-methyl- $11\beta,21$ -dihydroxy-3,5,17(20)-[*cis*]-pregnatriene was decanted from the precipitated inorganic salts and the salts then extracted with two 25-ml. portions of ether. The ether phase and ether extracts were combined and then mixed with a solution of 3 ml. of acetic acid in 15 ml. of methanol, thereby producing the minimum acid addition salt. 37 ml. of 10% aqueous sodium hydroxide was immediately added to the acidic mixture which was then stirred for 15 minutes. 40 ml. of water was added and the ether layer separated. The aqueous layer was extracted with 40 ml. of ether and the ether extract and ether layer combined and then washed successively with dilute hydrochloric acid, water, aqueous sodium bicarbonate and then saturated aqueous sodium chloride solution. The ether was dried over sodium sulfate and then distilled leaving a 3.2 g. residue of $11\beta,21$ -dihydroxy-4,17(20)-[*cis*]-pregnadien-3-one. Purification of this compound by crystallization from ethyl acetate gave 1.5 g., a yield of 44% of the theoretical calculated from the starting

4

3,11 - diketo - 6α - methyl - 4,17(20) - [*cis*] - pregnadien-21-oic acid methyl ester, of crystals melting at 172-174° C., having an $[\alpha]_D$ of +125° (CHCl_3) and a

$\lambda_{\text{max.}}^{\text{Hc}}$ of 242, a_M 14,850

Following the above procedure, comparable results are obtained by substituting an equivalent amount of methanolic hydrogen chloride for the acetic acid or the corresponding trans isomer as starting compound.

We claim:

1. In a process for the hydrolysis of the 3-pyrrolidyl enamine of 6α -methyl- $11\beta,21$ -dihydroxy-4,17(20)-pregnadien-3-one under alkaline conditions to produce 6α -methyl- $11\beta,21$ -dihydroxy-4,17(20)-pregnadien-3-one, the improvement which comprises converting the 3-enamine to an acid addition salt thereof prior to the alkaline hydrolysis.
2. The process of claim 1, wherein the acid addition salt is an organic acid addition salt.
3. The process of claim 1, wherein the acid addition salt is a lower-hydrocarbon carboxylic acid addition salt.
4. The process of claim 1, wherein the acid addition salt is the acetate.
5. The process of claim 1, wherein the starting compound is 3-pyrrolidyl-6-methyl- $11\beta,21$ -dihydroxy-3,5,17(20)-[*cis*]-pregnatriene and the acid addition salt is the acetate.
